FIG. 1.

FIG. 3.

FIG. 2.

FIG. 4.

Figure 1 is a perspective view of a coupling pin, showing my new design.

Figure 2 is a side elevation thereof.

Figure 3 is an end elevation.

Figure 4 is a bottom plan view.

My design for a coupling pin is characterized by the specific configuration of the handle element thereof, together with the knurling on the under-surface of the handle projections.

I claim:

The ornamental design for a coupling pin, as shown and described.
